UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A COUNTRY HOUSE.

SPECIFICATION forming part of Design No. 19,370, dated October 22, 1889.

Application filed September 28, 1889. Serial No. 325,453. Term of patent 3½ years.

To all whom it may concern:

Be it known that I, ANTOINE LACROIX, Jr., of the city of Brooklyn, in the county of Kings and State of New York, have invented and produced a new and original Design for the Exterior of a Country House, of which the following is a specification, reference being had to the accompanying drawings, forming a part thereof.

10 Figure 1 represents a perspective view of a country house showing my design. Fig. 2 represents a horizontal section or plan of the first story. Fig. 3 represents a horizontal section or plan of the second story.

15 Similar letters of reference designate corresponding parts in all the figures.

A house of this design consists of two stories, with an attic third story within a gable roof, the front having an octagonal bay in the 20 first story, a projecting flat face to the second story, and a gable to the third story, the first and second stories having a wing which is partly rectangular and from which projects a bay of polygonal form, the gable roof being 25 continued downward over the flat portions of the said wing and over a piazza which is formed in front of and at part of the side of the wing, the so downwardly-continued portion of the roof having within it a dormer 30 with a peaked roof, and the polygonal portion of the bay having a pyramidal roof, all as hereinafter more particularly described in detail with reference to the drawings.

35 A B C designate the front of the house, in which the first story has a bay A, the plan of which, as shown in Fig. 2, forms three sides of an octagon. The second story has a square front B, which projects over the said bay A, flush with the front thereof, and the 40 third story has a projecting gable C of the full width of the front, and which is included within the gable roof J. One side D is plain,

as shown in Figs. 2 and 3. The other side has a wing E F G, which extends from the ground to the top of the second story. The 45 portions F G of the said wing are plain and flat; but the portion E forms a bay projecting from the said plain portions F G, and which also reaches from the ground up to the top of the second story. This bay presents in 50 plan six sides of a polygon. On the first story the wing starts at about one-third of the distance back from the front of the house, as shown in Fig. 2, and is extended nearly to the rear thereof; but on the second story the 55 portion G of the wing is extended forward over the piazza H, the floor of which is level with the floor of the first story. This piazza takes in the whole projection of the bay E, whence it extends forward nearly to the front 60 of the house, and at the front end of it is the stoop L. On the second story the portion G of the wing is prolonged over the piazza H to form a portion of the roof thereof. The gable roof J is continued downward from the main 65 body of the house in a regular slope, as shown at J' in Fig. 1, to include the parts F G of the wing and the piazza H. Within that portion J' of the roof including the portions F G of the wing there is a dormer K, (see Figs. 70 1 and 3,) having a pyramidal roof K'. (Shown in Fig. 1.) The bay E has also a roof which is pyramidal on the end, as shown at E' in Fig. 1, and gabled, as shown at E'', between the said pyramidal portion E' and the main 75 roof J.

What I claim is—

The design for the exterior of a country house, substantially as herein shown and described.

ANTOINE LACROIX, JR.
